US0D1007669S

(12) **United States Design Patent** (10) **Patent No.:** **US D1,007,669 S**
(45) **Date of Patent:** **** Dec. 12, 2023**

(54) **BREATHING MASK PADDING**

(71) Applicant: **Easyform Medical (Dongguan) Limited**, Dongguan (CN)

(72) Inventor: **Yingying Li**, Dongguan (CN)

(73) Assignee: **EASYFORM MEDICAL (DONGGUAN) LIMITED**, Dongguan (CN)

(**) Term: **15 Years**

(21) Appl. No.: **29/715,608**

(22) Filed: **Dec. 3, 2019**

(30) **Foreign Application Priority Data**

Jun. 5, 2019 (CN) 201930289640.2

(51) **LOC (14) Cl.** **29-02**

(52) **U.S. Cl.**

USPC **D24/110.1**

(57) **CLAIM**

The ornamental design for a breathing mask padding, as shown and described.

DESCRIPTION

FIG. 1 is a perspective view of a breathing mask padding; FIG. 2 is a front elevational view of the design shown in FIG. 1;

FIG. 3 is a rear elevational view of the design shown in FIG. 1;

FIG. 4 is a right side elevation view of the design shown in FIG. 1;

FIG. 5 is a left side elevation view of the design shown in FIG. 1;

FIG. 6 is a top plan view of the design shown in FIG. 1; and, FIG. 7 is a bottom plan view of the design shown in FIG. 1.

1 Claim, 7 Drawing Sheets
